UNITED STATES PATENT OFFICE.

JOSEPH F. LEMONS, OF ADAMS, TENNESSEE, ASSIGNOR OF ONE-FOURTH TO W. B. WINTERS, OF ADAMS, TENNESSEE, AND ONE-FOURTH TO JOHN HANCOCK, OF SPRINGFIELD, TENNESSEE.

DUST GUN.

1,423,125.

Specification of Letters Patent.

Patented July 18, 1922.

Application filed October 15, 1921. Serial No. 507,991.

To all whom it may concern:

Be it known that I, JOSEPH F. LEMONS, a citizen of the United States, residing at Adams, in the county of Robertson and State 5 of Tennessee, have invented certain new and useful Improvements in Dust Guns, of which the following is a specification, reference being had to the accompanying drawings.

10 This invention relates to certain improvements in dust guns and has relation more particularly to a device of this general character especially designed and adapted for use in spraying foliage and the like with powder for protecting them from insects, and it is an object of the invention to provide a novel and improved device of this general character whereby the requisite draft or blast may be created by means of 20 which the dust or powder may be distributed.

It is also an object of the invention to provide a device of this general character with novel and improved means whereby the dust 25 or powder within the containing hopper may be properly delivered or fed to a distributing tube to be acted upon by an air blast.

The invention consists in the details of 30 construction and in the combination and arrangement of the several parts of my improved dust gun whereby certain important advantages are attained and the device rendered simpler, less expensive and otherwise 35 more convenient and advantageous for use, as will be hereinafter more fully set forth.

The novel features of my invention will hereinafter be definitely claimed.

In order that my invention may be the 40 better understood, I will now proceed to describe the same with reference to the accompanying drawings, wherein:

Figure 1 is a view in side elevation of a 45 dust gun constructed in accordance with an embodiment of my invention, the discharge end of the delivery conduit or pipe being broken away;

Figure 2 is a view in top plan of the device as illustrated in Figure 1;

50 Figure 3 is a longitudinally vertical sectional view taken through the device as herein embodied;

Figure 4 is a horizontal sectional view taken longitudinally through the hopper

and casing, certain of the parts being in top 55 plan; and

Figure 5 is a fragmentary transverse sectional view taken through the wall of the hopper and the bearing carried thereby.

As disclosed in the accompanying drawings, H denotes a hopper of predetermined capacity and which has its upper end open and associated with said open end is a sliding closure member 1. Extending beneath the hopper H is an elongated delivery conduit or pipe 2, said conduit and hopper being in communication one with the other through an opening or port 3.

The hopper H is positioned intermediate the ends of the conduit or tube 2 and disposed on one end portion of the conduit or tube 2 is a fan casing 4 having the outlet thereof in communication with the conduit or pipe 2. The casing 4 is spiraloid in side elevation and has disposed therein a fan 5 70 arranged at substantially the center of the spiral whereby the casing forms about the fan a constantly increasing path toward the discharge thereof for the passage of the air.

The fan 5 is fixed to a shaft 6 and carried 80 by said shaft 6 within the casing 4 is a beveled pinion 7. The fan casing 4 and the hopper H are connected by a bracing member 8 whereby additional rigidity is imparted to the assembled device. The casing 4 85 adjacent the pinion 7 is provided with a removable side plate 9 herein disclosed as circular in form and the central portion of said plate 9 is provided with a slot or opening 10 through which extends a portion of a gear 90 11 meshing with the pinion 7 hereinbefore referred to.

The portion of the gear 11 exteriorly of the casing 4 is contained within a housing or boxing 12 provided with a forwardly disposed extension 14 providing a bearing for the shaft 15. The shaft 15 extends within the housing or boxing 12 and the gear 11 is fixed thereto. The housing or boxing 12 is adapted to contain grease or other suitable lubricant and in order to apply such lubricant, the housing or boxing 12 is provided with a filling vent 16 normally closed by the plug 17 or the like.

Connecting similar side faces of the housing H and the casing 4 is a sleeve 18 through which the shaft 15 is directed, the end portion of the shaft 15 remote from the boxing

12 being mounted in a bearing 19. The bearing 19 is carried by a plate 20 fixed to a side wall of the hopper H. The bearing 19 is provided with an oil opening 21 to facilitate 5 the desired lubrication of the portion of the shaft 15 within the bearing 19.

The bearing 19 at its outer end is continued by a housing 22 for a beveled pinion 23 fixed to the adjacent end of the shaft 15 and 10 said housing 22 is also provided with an oil opening 24. The pinion 23 meshes with a gear 25 fixed to one end portion of a shaft 26 rotatably supported by the hopper exteriorly thereof and extending transversely of 15 the hopper. The end portion of the hopper remote from the gear 25 is provided with an operating member 27 herein disclosed as a crank.

Rotatably mounted within the hopper H 20 approximately vertically above the opening 3 is a shaft 27, said shaft extending exteriorly of the hopper H through the plate 20. The shaft 27 has secured thereto interiorly of the hopper H an agitating element 28 25 herein shown as a brush.

Secured to the exterior or extended portion of the shaft 27 is a member or hub 29 provided at substantially diametrically opposed points with the outstanding and radially disposed members 30 and 31. The member 30 extends in a direction away from the gear 25 and has secured thereto an end portion of a retractile member 32, the opposite end portion of the member 32 being anchored, as at 33, to the adjacent side wall of 35 the hopper H at a point in close proximity to its open or upper face. The retractile member 32 is herein disclosed as a coiled spring and serves to automatically impart 40 rocking movement to the shaft 27 in one direction.

The second member 31 is of a length to terminate in close proximity to the periphery of the gear 25. The gear 25 has extending 45 outwardly from its periphery a plurality of circumferentially and preferably equidistantly spaced teeth or lugs 34 whereby, upon rotation of the gear 25, the lugs or teeth 34 engage the member 31 and intermittently 50 rock or oscillate the shaft 27 in one direction. The spring 32 under normal conditions, or before being expanded, operates to maintain the member 31 in a position for engagement with the lugs 34.

55 The forward or discharge end portion of the tube or conduit 2 may be provided with a suitable nozzle (not shown).

In practice, the assembled device is supported upon the body of a person or otherwise 60 and the hopper H being first filled with a dust or powder destructive to insect life, the handle is utilized to rotate the gear 25 through the medium of the shaft 26. The rotation of the shaft 26 is transmitted 65 through the gear 25 and the shaft 15 to the

fan 5 with a much increased speed, thereby producing a blast or current of air through the tube or conduit 2 to effectively discharge the dust or powder delivered within the tube or conduit 2 through the opening 3.

70 As the gear 25 rotates, the lugs or teeth 34, together with the retractile member or spring 32, effects an oscillation of the element or brush 28 and at each oscillation of said member or brush 28, a certain amount of powder or dust within the hopper H is delivered within the tube or conduit 2.

75 The side wall of the casing 4 remote from the plate 9 is provided with a suitable opening 35 to provide for the requisite ingress 80 of air within the casing 4 during the operation of the fan 5.

85 From the foregoing description it is thought to be obvious that a dust gun constructed in accordance with my invention is particularly well adapted for use by reason of the convenience and facility with which it may be assembled and operated, and it will also be obvious that my invention is susceptible of some change and modification 90 without departing from the principles and spirit thereof and for this reason I do not wish to be understood as limiting myself to the precise arrangement and formation of the several parts herein shown in carrying out my invention in practice except as hereinafter claimed.

95 I claim:

1. In a dust gun, a hopper, a delivery tube associated with the hopper and in communication therewith, a rock shaft mounted within the hopper above the communication between the hopper and tube, an agitating member carried by said shaft, a fan casing having an outlet communicating with one end of the delivery tube, a rotary blower fan within the casing, a second shaft rotatably carried by the hopper, a member fixed to 100 said second named shaft and operatively connected with the fan to rotate the same, oppositely directed members carried by the rock shaft, means associated with one of said last named members for automatically turning the rock shaft in one direction, the second of said last named members closely approaching the gear, and circumferentially spaced lugs carried by the gear for contact with the second of said last named members to intermittently move the rock shaft in a 105 second direction.

110 2. In a dust gun, a hopper, a delivery tube associated with the hopper and in communication therewith, a rock shaft mounted within the hopper above the communication between the hopper and tube, an agitating member carried by said shaft, a fan casing having an outlet communicating with one end of the delivery tube, a rotary blower fan within the casing, a second shaft rotatably carried by the hopper, a 115

120

125

130

member fixed to said second named shaft and operatively connected with the fan to rotate the same, oppositely directed members carried by the rock shaft, a retractile 5 member associated with one of said last named members for automatically turning the rock shaft in one direction, the second of said last named members closely approaching the gear, and circumferentially 10 spaced lugs carried by the gear for contact with the second of said last named members to intermittently move the rock shaft in a second direction.

3. In a dust gun, a hopper, a delivery tube 15 associated with the hopper and in communication therewith, a rock shaft mounted within the hopper above the communication between the hopper and tube, an agitating member carried by said shaft, a fan casing

having an outlet communicating with one 20 end of the delivery tube, a rotary blower fan within the casing, a second shaft rotatably carrier by the hopper, a member fixed to said second named shaft and operatively connected with the fan to rotate the same, 25 oppositely directed members carried by the rock shaft, a spring associated with one of said last named members for automatically turning the rock shaft in one direction, the second of said last named members closely 30 approaching the gear, and circumferentially spaced lugs carried by the gear for contact with the second of said last named members to intermittently move the rock shaft in a second direction.

In testimony whereof I hereunto affix my signature.

JOSEPH F. LEMONS.
